LENS AXIS ALIGNING DEVICE

William J. Schmidt, Independence, Mo., assignor
to American Optical Company, Southbridge,
Mass., a voluntary association of Massachusetts

Application April 23, 1948, Serial No. 22,913

10 Claims. (Cl. 33—180)

1

This invention relates to lens axis aligning devices and has particularly reference to an improved device for accurately locating a lens blank in proper axial position in an abrading fixture.

One of the principal objects of this invention is to provide means for axially aligning an ophthalmic lens blank with respect to the axis of a fixture used for supporting said blank in proper axial position during a subsequent surfacing operation.

Another object is the provision of means in a device of the above character which will indicate the condition of wear of the axis retaining parts of the fixture in which the lens blank is axially supported.

Another object is the provision of a device of the above character which is simple in construction and which permits the axis of an ophthalmic lens blank, while carried by lens holding means, to be quickly, efficiently and positively aligned with respect to the axis of a fixture used for supporting the blank and holder in proper axial position during a subsequent surfacing operation.

With these and other objects in view, the present invention will be more clearly understood and the advantages thereof fully realized from the following description read in conjunction with the accompanying drawing in which:

Fig. 1 is a front elevational view of a device embodying the invention;

Fig. 2 is a top plan view of the invention;

Fig. 3 is a fragmentary sectional view taken on line 3—3 of Fig. 2;

Fig. 4 is a sectional view taken on line 4—4 of Fig. 1;

Fig. 5 is a fragmentary top plan view of a lens blank and a lens supporting bridle, illustrating particularly the method of performing the axis aligning operation; and

Fig. 6 is a sectional view showing a modification of the means for retaining the axis aligning wire in position.

In the manufacture of articles such as ophthalmic lenses, in many instances it is essential that the lenses be provided with surface curvatures in designated meridians exactly as described. Therefore, when a lens blank has been marked with an axis line or lines and blocked according to the customary practice in the manufacture of such articles, it is essential that the lens blank be aligned in a surfacing machine on an axis coincident with the axis on which the blank was blocked. That it, when a lens blank is blocked, it is positioned with respect to its cylinder axis as well as other factors of

2

the finished prescriptive power which the resultant lens is to possess and is fixedly attached to and retained by a block while in that position. Since a blocked lens blank must be surfaced in accordance with the position of the blank as determined during the blocking operation, it is essential, if the blank is to be surfaced accurately, that it be transferred to a surfacing machine with its axis exactly as positioned during the blocking operation.

Heretofore, it has been the general practice to insert a lens blank in a surfacing machine by merely relying upon the operator's eyesight to align the blank in the bridle so that when the bridle is inserted in a surfacing machine such as a cylinder grinder the blank will be axially aligned in the machine on the axis on which it was blocked, and subsequently surfaced. However, by relying only on the human element for accurate alignment, many inaccuracies resulted since a careless or inexperienced operator or an operator having defective vision might improperly position the blank with respect to its axis and, consequently, blanks may be inaccurately surfaced. In addition to this detrimental feature, it is possible that worn bridles might be used for supporting a lens blank to be surfaced, the worn bridle also causing the lens blank to be surfaced inaccurately. These objections are overcome by the present invention wherein there is provided an aligning device separate and independent of blocking or grinding machines.

Referring more particularly to the drawing wherein like characters of reference designate 35 like parts throughout the several views, the device embodying the invention comprises an aligning device 10 which may be fixedly secured to a bench or other suitable supporting means 11, such as by screws 12 which are adapted to extend 40 through an extension 13 formed integral with each end of the device. The device is provided with a pair of spaced abutments such as uprights 14 and 15 joined by a web portion 16, each upright 14 and 15 being provided with a projection or boss 17 and 18 respectively. The bosses 17 and 18 are located on the front surfaces of the uprights near the upper ends thereof and are each provided with narrow kerfs 19 and 20 respectively, the kerfs 19 and 20 being aligned 50 with respect to one another and located on the longitudinal axis of the bosses 17 and 18.

The boss 17 is provided with a longitudinal bore 21 axially aligned with the base of the kerf 19 and adapted to extend from the outer end of 55 the boss 17 partially into the boss. The boss

18 is provided with a shallow bore 22 which bore is axially aligned with the base of the kerf 20 and adapted to extend only partially into the outer end of the boss 18.

A plug 23 of such a size as to snugly reside within the bore 22 has a longitudinal bore therethrough into which is projected one end of an axis aligning member 24, which member may be made of any suitable finely drawn material such as piano wire or the like, a set screw 25 being provided in a transverse threaded opening in the plug 23 to be brought into abutment with the member 24 and by wedging action to thereby firmly retain the member 24 in position within the plug.

A threaded stud 26 is adapted to slidably reside in the bore 21 of boss 17 and provided with a longitudinal slot 27 in the bottom of which is adapted to reside the other end of the aligning member 24. A set screw 28 is also provided in the head of the stud 26 to secure the member 24 in the slot 27 in a manner similar to the set screw 25.

Upon locating the ends of the member within the bore in the plug 23 and in the slot 27 of the stud 26, and adjusting the set screws 25 and 28 to restrain the member 24 from displacement, the stud 26 and plug 23 may then be inserted within the bores 21 and 22 respectively with the aligning member 24 being adapted to extend from the stud 26 to the plug 23 in spanning relation between the bosses 17 and 18 and uprights 14 and 15 and to reside within the kerfs 19 and 20 in the bosses 17 and 18. To counteract slack in the member 24, adjusting nuts 29 and 30 are provided on the stud 26 adjacent the outer end of the boss 17 so that by tightening the nut 29 against the boss 17, the stud 26 will be drawn in the direction outwardly of the bore 21, thereby taking up the slack in the member 24, the nut 30 then being adapted to be tightened against the nut 29 to lock the parts in position and thus prevent the member 24 from becoming slack until the lock nut 30 is released.

A lens blank 31 to be surfaced is attached to a lens block 32 by suitable blocking means and is marked by one or more lines 33 indicating the predetermined cylinder axis of the lens blank. The lens block 32 is adapted to be positioned on a bridle 34, the bridle constituting a well known but important part of a toric or cylinder grinding machine such as may be used for performing the surfacing operation on the lens blank. The bridle 34 includes a substantially disk shaped holder 35 provided with a vertical circular opening disposed centrally thereof. The lens block 32 is adapted to be positioned upon the upper surface of the holder 35 and has its undersurface provided with a circular extension 36 adapted to rotatably reside within the vertical opening in the holder 35 and to be locked immovable therein by means of a set screw 37.

The holder 35 is provided with a pair of diametrically opposed arms 38 threadedly or otherwise connected thereto, the arms 38 being provided on each side thereof with engagement portions such as longitudinal fillers 39, the arms and fillers being accurately made and assembled so that the edges of the fillers are adapted to be positioned on a plane parallel with an axis through the center of the bridle 34. This feature is clearly illustrated in Fig. 5 wherein the aligning member or wire 24 is indicative of the center line through the holder 35 and arms 38, and it can be seen that the edges of the fillers

39 are parallel to this line throughout their entire lengths.

The uprights 14 and 15 are each provided with engagement or abutment portions having planar frontal surfaces 40, these surfaces being accurately machined parallel with the aligning member 24, the member 24 being disposed a distance to the front of the surfaces 40 equal to the distance between the edges of the fillers 39 and the center line of the bridle 34. This is clearly illustrated in Fig. 4 wherein it can be seen that the centers of the bridle arms 38 and the aligning member 24 are equidistant from the surfaces 40 on a common center line 41 drawn vertically through the bridle arms and the aligning member.

In performing an aligning operation, a lens blank 31 which has been previously attached to a lens block 32 and provided with axis lines 33 is placed upon the holders 35 with the extension 36 being movably disposed in the opening in the holder. Then, as illustrated in Figs. 1 and 2, the bridle 34 is placed by the operator against the uprights 14 and 15 and in spanning relation thereto with the edges of the fillers 39 in one side of the arms 38 being positioned against the machined surfaces 40 of the uprights and with the lens blank 31 positioned between the uprights and immediately below the aligning member 24. To align the blank 31 with the center of the bridle, the blank 31 is rotated until the axis lines 33 are disposed in alignment with the member 24. The set screw 37 is then tightened to prevent the blank from further rotation, and the bridle and lens blank may be then removed 35 from the device and inserted in a surfacing machine.

By this means, the lens blank is assured of accurate alignment with respect to the bridle so that upon insertion of a bridle and lens blank in a surfacing machine, the axis is definitely and accurately established and retained as determined by the previous blocking operation, and inaccuracies resulting from poor axial alignment are thus eliminated.

It is important that the dimensions between the center line of the bridle and outer edges of the fillers 39 be maintained. By this means the condition of the fillers may be checked since if it is found impossible to axially align a lens blank in the device this will indicate, if the lens blank has been accurately marked, that the fillers are worn and should be replaced.

It is conceivable that other means may be used to retain one end of the aligning member 24 such as the means illustrated in Fig. 6 wherein the opening 21 in the boss 17 is threaded to threadedly receive the stud 26, with a single lock nut 42 being used to retain the parts of the unit in place.

From the foregoing, it will be understood that the present invention overcomes many undesirable features of prior methods for axially aligning lens blanks with other devices by providing simple and efficient means for obtaining true alignment thereof by eliminating much of the human element, and further improving upon the prior art by providing such a device which will also indicate the worn condition of parts used therein, thus providing greater efficiency and more accuracy in such operations.

While certain novel features of the invention have been shown and described and are pointed out in the annexed claims, it will be understood that various omissions, substitutions and changes in the forms and details of the device illustrated

and in its operation may be made by those skilled in the art without departing from the spirit of the invention.

I claim:

1. In a device of the character described, a device for axially aligning a lens blank comprising a support having spaced uprights formed thereon, said uprights having abutment portions with aligned vertically disposed planar frontal surfaces, longitudinally disposed bosses formed on said uprights above said portions having the said planar surfaces and extending forwardly thereof, an elongated aligning member having its ends adjustably supported by said bosses and disposed at a distance forward of and parallel to the said planar surfaces, and a bridle adapted to carry the lens blank to be aligned comprising a holder having a vertical centrally disposed opening therein and having a pair of arms connected in diametrically opposed relation thereto, said arms having longitudinal engagement portions disposed in aligned relation, a lens block to which said lens blank may be connected provided with an extension adapted to rotatably reside in the opening in said holder, said bridle being adapted to be positioned against the uprights with said engagement portions in abutment with the planar surfaces of said uprights and with the lens blank positioned between the uprights and below said aligning member whereby the blank can be axially adjusted on the holder to bring the lens blank into axial alignment with the aligning member.

2. In a device of the character described, a device for axially aligning a lens blank having axis lines marked thereon comprising a support having spaced uprights formed thereon, said uprights having abutment portions with substantially vertically disposed planar frontal surfaces aligned in substantially the same plane, longitudinally disposed bosses formed on said uprights above said abutment portions having said planar surfaces and extending forwardly thereof, an elongated aligning member having its end adjustably supported by said bosses and disposed at a predetermined distance forward of and parallel to the said planar surfaces, and a bridle adapted to adjustably carry the lens blank to be aligned comprising a holder having a vertical centrally disposed opening therein and having a pair of arms connected in diametrically opposed relation thereto and having their longitudinal axes aligned with the axis of said holder, said arms having disposed thereon longitudinal engagement fillers of such size that the distance between the outer edges of said fillers and the longitudinal axis of said arms is in correspondence to the distance at which the aligning member is disposed forwardly of the planar surfaces of the uprights, a lens block to which said lens blank is connected, said lens block being adapted to be adjustably positioned on said holder and provided with an extension adapted to rotatably reside in the opening in said holder, said bridle being adapted to be positioned against the uprights with said engagement fillers in abutment with the plane surfaces of said uprights and with the lens blank positioned between the uprights and adjacent said aligning member whereby the blank can be adjusted on the holder to bring the longitudinal axis lines thereon into alignment with the aligning member.

3. An aligning device of the character described comprising a pair of spaced abutment portions joined by an integral web, said abutment portions

having on their same side engagement portions lying substantially in the same continuous plane and having an open area therebetween, and supports located to one side of and extending forwardly of the plane of said engagement portions, an aligning wire having its opposed ends secured to said supports and spanning the open area between said engagement portions, said wire being disposed at a predetermined distance forwardly of and extending in a direction substantially parallel with respect to the plane in which said engagement portions lie.

4. An aligning device of the character described comprising a pair of spaced abutment portions joined by an integral web, said abutment portions having planar frontal surfaces aligned to lie substantially in the same vertical plane and having an intermediate open area therebetween, and supports located above said abutment portions and extending forwardly of said surfaces, an aligning member secured to said supports and spanning the open area therebetween, said aligning member being disposed at a predetermined distance forwardly of and extending in a direction substantially parallel with respect to the plane in which said planar surfaces lie.

5. An aligning device of the character described comprising a base having a pair of spaced uprights and each having an engagement portion on the front side thereof, said engagement portions having an open area therebetween and being aligned with respect to each other to lie in the same vertical plane, supporting portions located above said engagement portions and projecting from said uprights and having aligned openings therein spaced equidistantly from and on the same side of the base as the plane in which said aligned engagement portions lie, a fine aligning wire having its ends secured in said openings in the supporting portions and spanning the open area between said engagement portions, said wire being disposed at a predetermined distance from and extending in substantially parallel relation to said plane in which the engagement portions are aligned, and locking means seated within said openings in the supporting portions for maintaining said wire taut.

6. An aligning device of the character described comprising a base having a pair of spaced uprights joined by an integral web and each having a planar surface on the front side thereof, said planar surfaces being aligned with respect to each other to lie in the same vertical plane and being separated by an open area therebetween, supporting portions located above at least a portion of said planar surfaces and projecting from said uprights, said supporting portions having aligned openings therein spaced equidistantly from and on the same side of the base as the plane in which said aligned planar surfaces lie, a relatively fine aligning wire having its ends mounted in the openings in each of the respective supporting portions and spanning the open area between said planar surfaces, said wire being disposed at a predetermined distance from and extending in spaced substantially parallel relation to said plane in which the said surfaces are aligned, and locking means seated within said openings in the supporting portions for maintaining said aligning wire in taut assembled relation therewith.

7. A device for axially aligning a lens blank having axis marks thereon comprising a pair of spaced abutment portions lying in substantially the same plane and separated by an open area, a lens blank holder adapted to extend within said

open area and having a pair of diametrically opposed arms, said arms having engagement portions disposed in substantially the same plane and to engage said abutment portions, an aligning member mounted to one side of said engagement portions and located at a predetermined distance forwardly of and in substantially parallel relation with the plane in which said abutment portions lie and substantially coincident with the longitudinal axis of said arms of the holder, and said holder having means for rotatably supporting the lens blank thereon, whereby said lens blank may be rotated to cause said axis marks thereon to be brought into coincidence with the aligning member.

8. A device for axially aligning a lens blank having axis marks thereon comprising a pair of spaced planar surfaces lying in substantially the same plane and separated by an open area, a lens blank holder adapted to extend within said open area and having a pair of diametrically opposed arms, said arms having engagement portions with surfaces disposed in substantially the same plane and to engage said planar surfaces, an aligning member mounted to one side of the portion of said planar surfaces to be engaged by said arms and in a predetermined spaced substantially parallel relation with the plane in which said planar surfaces lie and substantially coincident with the longitudinal axis of said arms of the holder, and said holder having rotatable means for supporting the lens blank thereon, whereby said lens blank may be rotated to cause said axis marks thereon to be brought into coincidence with the aligning member, and locking means on said holder for maintaining said lens blank immovable when rotated to a desired position.

9. A device for axially aligning a lens blank having axis marks thereon comprising a pair of spaced planar surfaces lying in substantially the same plane and separated by an open area, a lens blank holder adapted to extend within said open area and having a pair of diametrically opposed arms, said arms each having an engagement portion with a surface along its length disposed in substantially the same plane and to engage said planar surfaces, an aligning member mounted to one side of the portions of said planar surfaces to be engaged by said arms of

the holder and in substantially parallel spaced relation with the plane in which said surfaces lie and substantially coinciding with the longitudinal axis of said arms, and said holder having 5 a centrally disposed opening for rotatably supporting a lens block having a lens blank secured thereon, whereby said lens block may be rotated to cause said axis marks on the lens blank to be brought into coincidence with the aligning member, and locking means for rendering said lens block immovable.

10. A device for axially aligning a lens blank comprising a support having spaced uprights provided with abutment portions having aligned 15 planar frontal vertical surfaces, an aligning member supported above said abutment portions having planar surfaces and at a distance spaced from and substantially parallel to said planar surfaces, and a holder having a pair of diametrically opposed laterally extending arms and an adjustable central portion for supporting the lens blank, said laterally extending arms each having a portion provided with a longitudinal engagement surface disposed in aligned relation, 20 and said arms of the holder being adapted to be positioned against said abutment portions of the uprights with said engagement surface in abutment with the planar surfaces of said portions of the uprights and with the lens blank positioned between the uprights and adjacent said aligning member whereby the blank may be adjusted on said central portion of the holder to bring the lens blank into axial alignment with the aligning member.
